(57) **CLAIM**

The ornamental design for an electronic device mount for vehicles, as shown and described.

DESCRIPTION

FIG. 1 is a front perspective view of an electronic device mount for a vehicle in a closed position, the mount being comprised of a base and a cover, showing my new design; FIG. 2 is a rear perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front exploded perspective view thereof; FIG. 10 is a rear exploded perspective view thereof; FIG. 11 is a front perspective view of the electronic device mount for the vehicle in an open position; FIG. 12 is a rear-perspective view thereof; FIG. 13 is a front elevational view thereof; FIG. 14 is a rear elevational view thereof; FIG. 15 is a left side elevational view thereof; FIG. 16 is a right side elevational view thereof; FIG. 17 is a top plan view thereof; FIG. 18 is a bottom plan view thereof; and, FIG. 19 is a front perspective view thereof, illustrating an electronic device in broken lines.

The broken line showing of environment is for illustrative purposes only and forms no part of the claimed design.

1 Claim, 19 Drawing Sheets
